UNITED STATES PATENT OFFICE.

CHARLES M. BAKER, OF KANSAS CITY, MISSOURI.

TRACTION MECHANISM.

1,216,398.

Specification of Letters Patent. Patented Feb. 20, 1917.

Application filed July 15, 1914. Serial No. 841,118.

To all whom it may concern:

Be it known that I, CHARLES M. BAKER, a citizen of the United States, residing at Kansas City, in the county of Jackson and State of Missouri, have invented certain new and useful Improvements in Traction Mechanisms, of which the following is a full, clear, and exact description, such as will enable others skilled in the art to which it appertains to make and use the same.

The invention relates to traction mechanisms for propelling agricultural implements, such as plows, harvesters, wagons and the like.

15 Traction engines are used for plowing, threshing grain and the like, but the construction heretofore has been such as to limit their use, owing to the excessive room required for turning the machine at the end 20 of the field. The turning of the machine has been accomplished by changing the angle of the wheels and applying the power so that the machine will travel in a circle, this requires a circuit at each end of the 25 field, or moving the machine forward and backward alternately, changing the angle of the wheels for each movement until the machine is turned to the desired position. These movements at each end and often at 30 each corner of the field require a certain amount of ground that cannot be cultivated, resulting in the loss to cultivation of valuable land, and usually a portion of the land that is cultivated becomes so compacted by 35 the wheels of the machine that it is worthless for producing purposes.

It is essential that traction mechanism for agricultural purposes be so constructed that a forward or backward movement of 40 the machine will not be required to turn the machine to any angle or completely around end for end, so that plows or harvesters may be run to the end of the field and turned as on a pivot to the position for 45 the return trip, or to a right angle position in the case of turning a corner, to avoid the waste of land as heretofore.

The present invention seeks to provide an improved traction mechanism that may 50 be detachably attached to the ordinary implement, as a plow, harvester, wagon and the like, allowing the implement to carry one end of the mechanism and providing means for turning the machine without forward or backward movement.

By being able to move one end of the

machine in any horizontal direction the machine may be turned completely around without changing the position of one of the wheels of the opposite end of the machine, which enables the operator in plowing to run the plows to the end of the field and turn around without making a circuit, placing the plows facing the opposite direction and immediately along side of the strip 60 of land just completed or plowed.

65 The tractor wheel of the present invention may be turned to an angle that will pivot the machine at any desired point of the opposite end so that the return trip may be started in the same place, or immediately 70 along side, or in any desired place, which is very advantageous in propelling plows, harvesters and the like.

A further object of the invention is to 75 reduce the friction, the elimination of differential gears and general simplicity being large factors in this direction.

A still further object of the invention is to reduce the cost of the mechanism so that 80 it may supplant the horse and not only reduce the cost of agricultural work, but also reduce the cost of the equipment of the ordinary farm, the elimination of differential gears and general simplicity of construction being large factors in this direction.

With these and other objects in view, the invention consists in the features of construction, combinations and arrangements 85 of parts hereinafter set forth illustrated in the accompanying drawings and more particularly pointed out in the claims appended.

In the drawings:—

Figure 1 is a view in elevation of the improved traction mechanism with a portion broken away to show the construction of the interior.

Fig. 2 is a view in elevation of the mechanism attached to a cultivator plow.

Fig. 3 is a plan view of the mechanism attached to a cultivator plow.

Fig. 4 is a plan view illustrating the connection of the mechanism to a harvester.

Fig. 5 is a plan view illustrating the connection of the mechanism to a wagon.

Fig. 6 is a fragmentary view in elevation with the tractor wheel turned at a right angle to the line of travel and with certain parts shown in section, the section being taken on line a of Fig. 3.

Fig. 7 is a fragmentary sectional view on the same line as Fig. 6, but showing a slightly different arrangement of the gearing.

5 Fig. 8 is a view in elevation of the mechanism attached to and forming part of the usual traction engine.

Fig. 9 is a plan view of the mechanism attached to and forming part of the usual 10 traction engine.

The traction wheel 1 is journaled on shaft 2 and provided with sprocket wheel 3 which is secured to the hub 4 of the wheel, the shaft extending either side of the wheel and 15 through the yoke 5 and being secured therein by nuts 6.

The yoke 5 is provided with the horizontally disposed circular ball track 7 which is a companion to the ball track 8 of the 20 drum 9, the balls 10 forming a bearing by which the drum and connections are supported by the yoke, the balls forming a bearing in all horizontal directions as well as vertically. The yoke extends upward within 25 in the drum 9 and is provided with bearings 11 to receive the shaft 12, the upper end 13 of the yoke being journaled in the drum 9.

Secured to the shaft 12 is sprocket wheel 30 14 from which the chain 15 drives the sprocket 3 and wheel 1, the shaft also having secured thereto the bevel gear 16, the latter meshing with gear 17 shown integral with gear 18 and journaled on the bearing 35 19 of the yoke 5.

The drum 9 is provided with the bearing box 20 in which is journaled the shaft 21, the end of the shaft protruding within the drum and having rigidly mounted thereon 40 the pinion 22 which meshes in gear 18.

It will be understood from the foregoing that if shaft 21 be rotated the wheel 1 will rotate no matter at what angle it may stand with reference to the position of shaft 21.

45 The shaft 21 is journaled in box 23 and has rigidly mounted thereon the bevel gear 24 into which mesh the clutch bevel gears 25 and 26, the clutch gears being loosely mounted on the shaft 27 and engaged and 50 disengaged by clutches 28 and 29 respectively, the clutches being operated by bell-crank lever 30, bar 31, and handle bar 32.

The shaft 27 is driven by sprocket wheel 33, chain 34, and sprocket wheel 35, the 55 latter being rigidly mounted on the shaft 36 of the engine 37.

It is obvious that if clutch 28 be engaged shaft 21 will be revolved in one direction while if clutch 29 be engaged shaft 21 will 60 rotate in the opposite direction, therefore no matter which way shaft 36 of the engine 37 is rotated shaft 21 may be operated in either direction and the wheel 1 turned in either direction at will.

65 Extending outward from ball track 7 and

as shown integral therewith is sprocket wheel 38 which is driven with chain 50 from sprocket 39 secured to the shaft 40, the latter being driven by bevel gear 41 secured to shaft 40 and by clutch gears 42 and 43 70 mounted on shaft 21, the clutch gears being engaged to and disengaged from the shaft by clutches 44 and 45 respectively, the clutches being operated by levers 46, 47 and 48, and reach rod 49.

The clutch coupling 60 is provided in 75 shaft 21 and operated by lever 51 and reach rod 52 for the purpose of disconnecting the driving mechanism from wheel 1 when it is desired to revolve wheel 1 in a horizontal 80 direction and not rotate the wheel in the direction of its circumference.

From the foregoing it will be understood 85 that the wheel 1 may be revolved horizontally in either direction without being rotated circumferentially, the advantage being that when the end of a field is reached the rotation of the wheel may be stopped and the wheel revolved horizontally to slightly beyond a right angle to the line of travel, 90 after which the wheel may be rotated in the direction of its circumference and the machine turned end for end without longitudinal movement, placing the machine immediately along side of where the last trip was 95 finished. It is obvious that the angle of wheel 1 may be so regulated as to turn the machine so that the longitudinal center thereof will be in the same line as that occupied before turning, or that the wheel may 100 be so set as to move the machine to one side while turning, and the side movement may be so regulated as to accommodate the width worked by the machine.

The frames 53 extend from the drum 9 105 and support the engine 37 and intermediate parts, the frames being connected to the axle 54 by bolts 55, the axle being supported by wheels 56 journaled thereon, and the plows 57 being connected to the frame by 110 hangers 58 and bolts 59.

In Fig. 4 the mechanism is shown connected to a harvester, and in Fig. 5 connected to a wagon, the purpose of the views being to show that the mechanism may be of universal use in the propelling and working of 115 implements such as are used in agricultural pursuits.

In Figs. 8 and 9 the mechanism is shown connected to the usual form of traction engine in which connection the wheel 1 may be used to assist in propelling and for turning, or only for turning as desired, the traction engine being of well known and usual construction is not further described. 120

Having described my invention, what I claim and desire to secure by Letters Patent is:—

1. In traction mechanism, a frame, a housing secured to and rising above said 125

frame, a journal bearing in said housing, a shaft journaled in said bearing and disposed longitudinally of said frame, a beveled pinion on said shaft within said housing, means to revolve said shaft in opposite directions, a vertically disposed shaft journaled in said housing, a double faced beveled gear journaled on said shaft, the teeth of the upper face of said vertically disposed double faced 10 beveled gear meshing with said pinion, a pair of arms projecting downwardly from said vertically disposed shaft, journal bearings carried by said arms, a horizontal shaft journaled in said journal bearings, a gear rigidly mounted on said horizontal shaft and meshing with the teeth on the lower side of said double faced beveled gear, a sprocket wheel rigidly mounted on said horizontal shaft, a horizontal shaft journaled in said arms below said journal bearings, a traction and steering wheel on said last mentioned shaft, a sprocket wheel encircling said last mentioned shaft and rigidly connecting to said traction and steering 20 25 30 wheel, a sprocket chain connecting said sprocket wheels, and means connecting to said arms and supporting said frame.

2. In traction mechanism, a frame, a housing secured to and rising above said frame, a journal bearing in said housing,

a shaft journaled in said bearing and disposed longitudinally of said frame, a beveled pinion on said shaft within said housing, means to revolve said shaft in opposite directions, a vertically disposed shaft journaled in said housing, a double faced beveled gear journaled on said vertically disposed shaft, the teeth of the upper face of said double faced beveled gear meshing with said pinion, a pair of arms projecting downwardly from said vertically disposed shaft, journal bearings carried by said arms, a horizontal shaft journaled in said journal bearings, a gear rigidly mounted on said horizontal shaft and meshing with the teeth on the lower side of said double faced beveled gear, a shaft revolvably mounted in said arms below said journal bearings, a traction and steering wheel on said last mentioned shaft, means revolvably connecting said horizontal shafts, and means connecting to said arms and supporting one end of said frame.

In testimony whereof I affix my signature in the presence of two witnesses.

CHARLES M. BAKER.
